FISHING LURE

Thomas W. Drake, 323 Lindale, Houston, Tex. 77022

Filed Dec. 20, 1968, Ser. No. 15,073

Term of patent 14 years

Int. Cl. D22—08

U.S. Cl. D22—29

FIG. 1 is an isometric view of the front side, one edge and the bottom of a fishing lure showing my new design;

FIG. 2 is an isometric view of the rear side and bottom thereof; and

FIG. 3 is a smaller scale, orthographic view of part of the rear side shown in FIG. 1, part of the bottom shown in FIGS. 1 and 2, and of the edge opposite the edge shown in FIG. 2.

The broken lines in FIG. 1 are for illustrative purposes only.

I claim:

The ornamental design for fishing lure, as shown and described.
